COSMETIC CONTAINER OR THE LIKE

Robert B. Hopgood, Cheshire, Conn., assignor to
The Eyelet Specialty Company, Waterbury,
Conn., a corporation of Connecticut

Application May 26, 1949, Serial No. 95,428

16 Claims. (Cl. 206—56)

1

My invention relates to cosmetic or the like containers, and in particular to such containers in which a carrier for lipstick or the like is propelled upon relative rotation of two parts.

In containers of the character indicated, it is important that a container assembled with lipstick or the like shall hold its retracted position during shipment and in spite of the vibration which may occur during shipment. From the standpoint of the user, it is desirable that the propelling action shall be as free as possible and yet that, when the closure cap is placed over the container, it shall not be possible for the lipstick to be propelled against the inside of the closure cap.

It is, accordingly, an object of my invention to provide an improved structure meeting the above requirements.

It is another object to provide such an improved structure wherein the parts which serve to retain the carrier against propulsion (when the cap is on) offer substantially no resistance to propulsion when the cap is removed.

It is also an object to provide an improved means for dogging a cosmetic container against operation as long as the closure cap is in place—the dogging action resulting from the fact of having placed the cap over the container, rather than from the action of placing the cap over the container.

It is a specific object to meet the above objects with a construction involving the assembly of no more parts than are required for present constructions.

It is another specific object to meet the above objects with a construction involving no unsightly parts and presenting a minimum apparent change in outer appearance, even when the closure cap is removed from the container.

Other objects and various further features of the invention will be pointed out or will occur to those skilled in the art from a reading of the following specification in conjunction with the accompanying drawings. In said drawings, which show, for illustrative purposes only, preferred forms of the invention:

Fig. 1 is a view in elevation of a cosmetic container incorporating features of the invention;

Fig. 2 is an enlarged fragmentary cross-sectional view, with certain parts viewed more or less in the plane 2—2 of Fig. 1;

Fig. 3 is a fragmentary view in elevation of a modification of the structure of Fig. 1;

Fig. 4 is a view similar to Fig. 2, but taken more or less in the plane 4—4 of Fig. 3;

2

Fig. 5 is a partly broken-away view in elevation of a further modification according to the invention; and

Figs. 6 and 7 are enlarged fragmentary views in partial section illustrating the cooperation of parts in the structure of Fig. 5.

Briefly stated, my invention contemplates latching means cooperating between two relatively movable members of a cosmetic container of the character indicated, in order to hold a given relative position of said members. The latching means may cooperate substantially only for the one relative position in which latching is to take place. The latching means may carry or engage means which may project or be projected exteriorly of the container casing; upon placement of the closure cap, the mere presence of the closure cap may serve to limit movement of the latch means and therefore effectively to dog the container against operation. In one form to be described, the latch is a radially deformable member that is deformable only (or substantially only) at the latching position, and the inner surface of the closure cap serves to limit the extent of radial deformation and, therefore, to prevent a movement past the latch position as long as the closure cap is in place. In another arrangement, the latch is generally axially movable and carries a radial projection which may axially abut the bottom of the skirt of the closure cap in order to limit latch action as long as the closure cap is in place.

Referring to Figs. 1 and 2 of the drawings, my invention is shown in application to a more or less conventional cosmetic container including a carrier cup 10 to be propelled axially within the container. The cup 10 may be formed with or carry radially projecting cam-follower means 11 for simultaneous engagement with cooperating cam slots in an inner tubular member or shell 12 and in an outer tubular member or sleeve 13. In the form shown, the slot 14 in the inner shell 12 is straight, and the slot 15 in the sleeve 13 is a spiral. The sleeve 13 may carry an outer tubular casing 16, and the inner shell may be formed with an enlarged base portion 17. For the arrangement shown, the carrier 10 will be propelled upwardly upon a clockwise or right-handed rotation of the base 17 relatively to the outer tubular casing 16. In accordance with the invention, I provide latch means including a deformable member resiliently to latch two of the relatively movable parts against movement past one relative position thereof, and in the form shown in Figs. 1 and 2, such latch means is effective between a

part carried by the outer tubular member or sleeve 13 and a part carried by the carrier 10. The latch means may include a finger struck out of the outer tubular casing 16 and having an inwardly facing cam surface, as defined by a simple bend 19, to be engaged by the projecting part or cam-follower means 11 of the carrier 10. The finger 18 may be aligned with the spiral slot 15 at the lower end thereof. I prefer that when the carrier 10 is in its bottom position, as when the cam-follower projection 11 is in the lower end of the spiral slot 15 or in the lower end of the straight slot 14, an extension 20 of the finger 18 will overstand the cam-follower projection 11. It will be appreciated that with the extension 20, it may never be possible for the cam follower 11 to foul or to fail to cooperate with the finger 18 regardless of the abuse to which the parts are put.

The finger 18 is preferably so formed that no part projects beyond the outer circumference of the outer tubular casing 16. However, the cam bend 19 in the finger 18 is preferably sufficient to produce a cammed throw of the finger 18 in excess of the normal clearance between the closure cap 21 and the outer tubular casing. Thus, it will be appreciated that, with the carrier in the down-position, and with the closure cap 21 placed over the container, a relative rotation of the base 17 and of the closure cap 21 will result merely in driving the finger 18 hard against the inner surface of the closure cap 21; the resulting deformation of the finger 18 will be insufficient to permit the cam follower 11 to pass the latch bend 19. There will, accordingly, be no propulsion of the carrier when the carrier cap is in place, and the carrier may thus be effectively dogged. When the closure cap is removed, however, the cam-follower means 11 may freely radially outwardly deform the finger 18 as it passes the bend 19. After passage of the bend 19, the latching parts will be free of each other and of the other parts rotatable relatively thereto, so that carrier propulsion may be free and unimpaired by friction of the latch parts.

In Figs. 3 and 4, I show a modification of the arrangements of Figs. 1 and 2, and in this modification the only change is in the formation of the deformable means constituting the latch. In Figs. 3 and 4, the deformable means is merely a generally circumferentially extending arcuate strip 23 formed out of the outer tubular casing 16. The strip 23 may overstand the spiral slot 15 in the sleeve 13, and again a radially inward bend, as at 24, may serve to produce a latching action between the skirt 23 and the outer end of the cam follower 11. It will be appreciated that, because of the arcuate extent of the two slots 25 defining the strip 23, any deformation arising out of the latch action may be evidenced by an outward bulging of the strip 23. If the closure cap 21 is placed over the container, then the inner surface of the closure cap 21 may serve to limit such outward bulging and, therefore, effectively to dog the latch. If the closure cap 21 is not in place, then the latching action may be readily overcome, and carrier propulsion may be free and unopposed by any latching parts for all relative positions except the latching position.

In Figs. 5, 6, and 7, I show an alternative arrangement according to the invention, in which the latching action is evidenced by a more or less axial (rather than radial) movement, and in this arrangement the bottom of the skirt of the closure cap may serve to dog the axial movement

of the latch. As explained in greater detail in the copending application of Thompson and Hopgood, Serial No. 95,452, filed May 26, 1949, an axially movable latching member 30 may be formed out of the sheet metal of the sleeve 13. The latch 30 may comprise essentially an arcuate circumferentially extending resilient arm 31 and a projection 32 for resilient engagement with a fixed projection or lug 33, which may be formed out of or carried by the inner shell 12. In the forms shown, the lug 33 is struck out of the radial ledge 34 of the base 17 of the inner shell 12, and the upper surface of the lug 33 may be arched (as shown in Fig. 5) to provide gentle axially directed camming coaction with the latch projection 32. The latch 30 may be generally of the form shown and described in the said copending patent application, but I prefer that the relationship in the present form shall be such that for substantially all relative positions of the parts except the latching position, the latching parts shall impose no residual friction on the system. Thus, for the position shown in Figs. 5 and 6, the latching projection 32 is slightly spaced off (or, at least, does not substantially drag on) the ledge 34 of the base 17.

The projection 32 may also serve as dogging means to hold a latched engagement of the parts. Thus, the projection 32 may extend radially beyond the outer circumference of the outer tubular casing 16 and in axial overlapping relation with the base or skirt of the closure cap 21. It will be appreciated that friction means (not shown) may cooperate between the closure cap and the outer tubular casing in order frictionally to hold the closure cap on the container and that, when thus frictionally held, the cap 21 may effectively dog the projection 32 against axially upward displacement. When the closure cap 21 is removed, as in Fig. 7, the cam surfaces of the lug 33 may cooperate with the latch 30 to cam the same axially upwardly (as shown in Fig. 7) in order to release the carrier from the down-position and to permit free further propulsion into an extended position.

It will be understood that the axial latch parts (latch 30 and lug 33) may be formed out of the tubular members 12-13 at almost any desired axial position in the container, and to permit free latch action a window may be provided in the outer tubular casing 16. In the form shown, however, I have preferred that this latching action shall take place near the base 17, and, therefore, the window 35 formed out of the outer tubular casing 16 need only be a relatively small and inconspicuous recess in the skirt of the outer tubular casing 16, as will be clear.

It will be appreciated that I have described relatively simple constructions permitting the dogging of cosmetic-container parts when the cover or closure cap has been placed thereon. The dogging action need not result from the action of placing the cap but rather from the fact of having placed the cap over the container. The latch and dog parts may be either axial or radial in action, and yet they need offer no frictional resistance to free propulsive action for any except the latching position of the parts. Finally, my constructions may present a neat appearance and may be fabricated without the use of any more parts than are conventionally employed in self-propelling cosmetic containers.

While I have described my invention in detail for the preferred forms shown, it will be understood that modifications may be made within

the scope of the invention as defined in the appended claims.

I claim:

1. In a cosmetic container or the like, two relatively rotatable tubular members and a carrier member to be propelled upon a relative rotation of said members, resilient latch means carried by one of said members normally in the path of movement of a part of another of said members, said part including a projection to engage and be resiliently engaged by said latch, said latch being free of said part for all relative positions of said one member and of said other member except substantially for a latching relative position thereof, whereby said latch means will be moved only when said tubular members are rotated substantially at said latching relative position, means movable exteriorly of said outer tubular member upon coaction of said latch with said projecting part, and a closure cap to fit over said outer tubular member and limit said exterior movement.

2. In a cosmetic container or the like, an inner shell, a sleeve rotatable about said shell, a carrier member within said sleeve and shell and including cam-follower means projecting for coaction with propelling cams in said sleeve and in said shell, an outer tubular casing about said sleeve, and deformable means on said casing including cam means normally in the path of movement of said cam-follower means, said deformable means being movable generally radially outwardly of said casing upon interception of said cam-follower means, and a closure cap fitting said casing and serving to limit the extent of cammed radially outwardly deformed movement, whereby a closure cap over said container may serve to prevent propulsion of said carrier past the point at which said cam-follower means would otherwise fully outwardly deform said deformable means.

3. In a cosmetic container or the like, two relatively rotatable tubular members with cooperating propelling slots, a carrier member including projecting means engaging said slots, an outer tubular casing including a deformable latch member struck out of the surface thereof and including a part normally in the path of movement of said projecting means for camming engagement with said projecting means, a closure cap, and means on said closure cap poised to intercept and thus to limit a cammed displacement of said deformable latch member.

4. In a cosmetic container or the like, two relatively rotatable tubular members, a carrier with radially projecting cam-follower means in engagement with propelling slots in said tubular members, a radially outwardly deformable member carried by said outer tubular member and including a part formed to be cammed generally radially outwardly upon coaction with said cam-follower means, said deformable member being engageable with said cam-follower means at one relative position of said members and being free of said cam-follower means for relative positions of said tubular members on both sides of said one relative position, and a closure cap including means limiting outward displacement of said deformable member.

5. A container according to claim 4, in which said deformable member is a finger with cam means near the free end thereof to engage said cam-follower means.

6. A container according to claim 5, in which said finger radially overlaps said cam-follower

means for positions of said cam-follower means on both sides of the latching position of said cam-follower means.

7. A container according to claim 4, in which said deformable member is a continuous strip supported at both ends by said outer tubular member and formed with a radially inwardly directed cam for coaction with said cam-follower means.

8. In a cosmetic container or the like, two relatively rotatable tubular members, a carrier member to be propelled by said tubular members upon relative rotation of said tubular members, an outer tubular casing including radially outwardly deformable means, said deformable means being normally completely contained within a cylinder defined by the outer circumference of said outer tubular casing, said deformable means including a radially inwardly directed cam, and abutment means on one of said members that is movable relatively to said casing, said abutment means being located for coaction with said cam for one relative position of said parts, said abutment means being effectively clear of said cam for relative positions of said tubular members on both sides of said one relative position, and a closure cap including means to limit the coaction between said abutment and said cam.

9. In a cosmetic container or the like, a carrier, two relatively rotatable tubular members including means to propel said carrier upon relative rotation of said tubular members, a deformable member to project radially beyond the outer circumference of said outer tubular member and carried for rotation with one of said tubular members, means carried by the other of said tubular members and effective at one relative position of said tubular members to deform said deformable member, said means and said deformable member being in mutual clearance relation for relative angular positions of said tubular members on both sides of said one relative position, whereby propulsion of said carrier may be relatively free and unimpeded by friction between said means and said deformable member except at said one relative position, and a closure cap including means to limit the deformation of said deformable member.

10. In a cosmetic container or the like, a carrier, two relatively rotatable members with means cooperating with said carrier to propel said carrier upon relative rotation of said members, a fixed abutment struck out of an otherwise continuous surface on the return of said members so as to be permanently displaced from said continuous surface, generally axially deformable latch means carried by the other of said tubular members and engageable with said abutment, means movable with said latch and projecting outwardly of the outer circumference of said outer tubular member, and a closure cap including means limiting a latching movement of said outwardly projecting means.

11. In a cosmetic container or the like, a carrier, two relatively rotatable tubular members including means for propelling said carrier upon relative rotation of said tubular members, the inner of said members including an enlarged base for finger engagement, abutment means carried by said inner tubular member near the base portion thereof and projecting axially above the enlargement of said base portion, axially deformable latch means carried for rotation with said outer tubular member, said latch means including a part projecting radially beyond the outer periphery of said outer tubular member, a clo-

sure cap for said container, and means effective upon placement of said closure cap to limit displacement of said outwardly projecting part.

12. A cosmetic container according to claim 11, in which said radially projecting part extends sufficiently for axial engagement with said closure cap.

13. A container according to claim 11, in which said radially extending part is a lug overstanding the enlargement of said base and in clearance with said enlargement.

14. In a cosmetic container or the like, a carrier, an inner shell, a sleeve, said inner shell and said sleeve including means cooperating with said carrier to propel said carrier upon relative rotation of said inner shell and of said sleeve, an axially movable latch carried for rotation with said sleeve, abutment means carried for rotation with said inner shell and engageable with said latch axially to propel said latch for one relative position of the parts, an outer tubular casing having a window formed therein, means movable by said latch and including a part pro-

jecting radially through said window, and a closure cap including means to intercept a latch propelled movement of said part projecting through the window.

15. A container according to claim 14, in which said part projecting through the window is a lug integrally formed on said latch.

16. A container according to claim 15, in which said latch is formed out of an axial end of said sleeve and in which said window is an opening recessed out of the skirt of said outer tubular casing.
